UNITED STATES PATENT OFFICE.

AUGUST HENKEL, OF NEWARK, NEW JERSEY.

COMBINED NAIL-FILE AND CUTICLE-KNIFE.

1,113,168.

Specification of Letters Patent.

Patented Oct. 6, 1914.

Application filed January 13, 1912. Serial No. 670,974.

To all whom it may concern:

Be it known that I, AUGUST HENKEL, a citizen of the United States, residing at Newark, in the county of Essex and State of New Jersey, have invented new and useful Improvements in Combined Nail-Files and Cuticle-Knives, of which the following is a specification.

The invention relates to manicure implements and has for an object to provide an implement embodying a nail file and cuticle blade.

The invention embodies, among other features, a blade having a nail file thereon, the said blade being movable on a casing on which is mounted a cuticle blade, the first mentioned blade being movable to actuate the cuticle blade for the purpose of moving the same into or out of the casing and locking the same in open position.

My invention further embodies a device in which the nail file can be used independently of the cuticle blade, the cuticle blade being in this instance folded within the casing, thus obviating any danger to the user and protecting the cuticle blade during the use of the nail file.

Reference is to be had to the accompanying drawings constituting a part of this specification, in which similar characters of reference denote corresponding parts in all the views, and in which—

Figure 1 is a perspective view of my device, showing the cuticle blade thereof in closed position. Fig. 2 is a face view of my device showing the cuticle blade in open position. Fig. 3 is a face view of the device, the cuticle blade being in closed position and a portion of the casing being broken away to disclose the underlying structure. Fig. 4 is a face view of the device, the cuticle blade being in open position with a portion of the casing being broken away to disclose the underlying structure. Fig. 5 is a perspective view of the nail file blade, detached from the casing. Fig. 6 is a perspective view of the cuticle blade detached from the casing.

Referring more particularly to the views, I employ a blade 10 provided with a nail file 11 and terminating at one end thereof in a pointed portion 12 and at the other end thereof in an integral shank 13 having a locking head 14 integrally formed on the outer end thereof, a cut away portion 15 being provided adjacent the locking head and an integral tongue 16 being arranged to pro-

ject outwardly from the blade 10 adjacent the inner end of the shank 13. A casing 17, having open ends and an open side, is pivotally mounted on the blade 10 at the point 18 so that the tongue 16 will lie within the casing 17 and the shank 13 will act as a closure for the open side of the casing, the locking head 14 being adapted to project into the casing. Pivotally mounted on the 60 casing 17 is a cuticle blade 19, the said cuticle blade being provided with notches 20, 21, the notch 20 being adapted to engage an end of the casing to limit the outward movement of the cuticle blade and the notch 21 being 65 adapted to be engaged by the locking head 14 to lock the cuticle blade in open position, the free end of the said cuticle blade being adapted to lie over the tongue 16 when the 70 cuticle blade is in closed position.

Now assuming that the cuticle blade is in closed position as shown in Fig. 1, when it is desired to open the same, the casing 17 is swung on the cuticle blade 10 and this movement of the casing will cause the end 80 of the tongue 16 to engage the free end of the cuticle blade 19 and move the same partially outward from the casing 17. The outwardly projecting part of the cuticle blade 19 is now grasped by the user and the 85 cuticle blade is swung into open position, it being understood that the notch 20, engaging a side of the casing, limits the outward movement of the knife. The casing is now swung toward the shank 13 so that 90 the shank will lie within the casing with the locking head 14 engaging the notch 21 to lock the cuticle blade 19 in open position, a flanged portion 22 of the cuticle blade being received in the cut away portion 15, the 95 cuticle blade being now in open and locked position with the shank 13 positioned to close the open side of the casing 17.

When it is desired to move the cuticle blade into closed position, the casing 17 is 100 swung away from the shank 13, after which the user grasps the free end of the cuticle blade and moves the same to partially closed position so that the free end of the cuticle blade will lie between the shank 13 and the 105 tongue 16. The casing 17 is then swung toward the shank 13 and this movement of the casing will cause the back of the free end of the cuticle blade to be engaged by the inner side of the shank 13, thus moving 110 the cuticle blade to a position entirely within the casing, with the locking head 14 en-

gaging the notch 20 to retain the cuticle blade in closed position and the shank 13 positioned to close the open side of the casing, thus preventing any dirt or dust from 5 entering the casing as will be readily understood.

From the foregoing description it will be seen that the cuticle blade 19, constituting one implement, is movable in a plurality of 10 directions on the casing 17 and into locked position relatively to the casing, by the action of the blade 11 constituting a second implement, the second implement being arranged on the casing to move the first implement into opening position, closed position or lock the first implement relatively 15 to the casing.

I claim:

1. As a new article of manufacture, a 20 combined nail file and cuticle knife comprising a casing, an implement mounted to swing on the casing, and a second implement having independent pivotal connection with the casing and terminating at one end in 25 spaced members, one of which is adapted to engage the first mentioned implement when the second mentioned implement is

actuated, to move the first mentioned implement out of the casing, the said other spaced member being adapted to engage the 30 first mentioned implement when the second mentioned implement is actuated to move the first mentioned implement into the said casing.

2. As a new article of manufacture, a 35 combined nail file and cuticle knife comprising a casing, an implement mounted to swing thereon, a second implement mounted to swing on the casing, a tongue on the second implement and adapted to engage the first mentioned implement to move the same out of the casing, a shank on the second implement and adapted to engage the first mentioned implement to move the same into the casing, and a locking head formed with 40 the shank for locking the first mentioned implement in open position on the casing.

In testimony whereof I affix my signature in presence of two witnesses.

AUGUST HENKEL.
